UNITED STATES PATENT OFFICE.

CHARLES B. GILMORE, OF CHICAGO, ILLINOIS, ASSIGNOR TO CHICAGO FORGING & MANUFACTURING COMPANY, OF CHICAGO, ILLINOIS, A CORPORATION OF ILLINOIS.

HOOD LATCH.

Application filed February 27, 1925. Serial No. 11,930.

To all whom it may concern:

Be it known that I, CHARLES B. GILMORE, a citizen of the United States, residing at Chicago, in the county of Cook and State of Illinois, have invented a certain new and useful Improvement in Hood Latches, of which the following is a specification.

My invention relates to a fastening device, and particularly to a device intended for use as an automobile hood latch. One object of the invention is to provide a device which will be used as a hood latch and which, while serving to hold the hood down, and closed, will also force the hood inwardly against its abutment, and will thus hold the hood against rattling. Another object is to provide a hood latch which operates independently of variations in position of the hood. Other objects will appear from time to time throughout the specification and claims.

My invention is illustrated more or less diagrammatically in the accompanying drawings wherein—

25 Figure 1 is a side elevation of my latch, showing it in position on the automobile;

Figure 2 is a front view of my latch, in position and illustrating various positions which it may assume;

30 Figure 3 is a vertical section through my latch;

Figure 4 is a horizontal section along the line 4—4 of Figure 3.

Like parts are designated by like characters throughout.

45 A is a portion of an automobile frame. To it is fastened an upstanding rib or rim or abutment member A¹, against which abuts the lower edge B of the hood cover, when the hood is closed. Fastened to the hood B is a locking member B¹ terminating in a conic cam section B². Mounted above the cam B² on the locking member is the hook element B³ which terminates in an inwardly turned finger or flange B⁴, the hook lying in a generally horizontal plane.

50 C is a shaft or pin terminating with a member C¹ adapted to be seated in and to be contained by the socket member C² secured to the frame A. The upper end of the pin C is necked as at C³ to engage a washer or collar C⁴.

Surrounding the pin or shaft C is the enclosing cylinder D. D¹ is a spiral spring 55 adapted to be compressed between the collar

C⁴ and the lower end of the cylinder D and thus adapted normally to thrust the cylinder D downwardly along the pin C. D² is a cam member on the cylinder D adapted to engage the conic cam member B² on the hood B. It is apertured as at D³, the aperture being adapted to receive the hook B³. I provide any suitable finger or hand piece at the top of the cylinder D, for example the handle D⁴, screw-threaded thereto.

It will be realized that whereas I have described and shown a practical and operative device that nevertheless many changes may be made in the size, shape, number, proportion and disposition of parts without departing from the spirit of my invention. I therefore wish my description and drawings to be taken as in a broad sense illustrative rather than as limiting me to my specific showing.

The use and operation of my invention are as follows:

When the hood is to be opened, the latch handle is raised and the locking cam portion D² is lifted from contact with the cam B² and may be rotated to disengage it from the hook B³. The whole latch may then be swung back freely in any direction, and the hood may be raised. When the latch is again to be used, the hood is closed, the handle portion D⁴ is raised, and with it the entire latch, and the loop formed by the aperture D³ is again engaged with the hook B³. When the handle D⁴ is released, the cam D² presses upon the opposed inclined face of the cam B², and thrusts the hood both downwardly and inwardly, thus at the same time holding it securely closed and preventing its rattling. The downward pressure of the spring D¹, thrusting the cam D² downwardly and outwardly along the cam surface B², locks the loop D³ securely against the hook B³, which prevents outward movement of the latch away from the hood. The lug or finger B⁴, projecting inwardly from the hook B³ makes it impossible for the latch to work laterally along the hook and escape from it.

The pin C, being mounted on a ball and socket or universal joint on the frame A, 105 does not constrain the latch to any particular position, and the position of the latch is determined by the position of the cam B² and the hook B³. The result is a peculiarly flexible and adaptable latch which operates 110

independent of changes in the relative position of the hood B and the abutment A¹, since the latch can freely swing about the pivot or socket member C², to take any position, and since the spring D¹ is operative irrespective of changes in position of the latch or cam D². The range of vertical adjustment is illustrated in Figure 1, the dotted lines illustrating the latch in position when the cam B² is considerably raised. The only limit is the size of the aperture D³, which of course may be varied to suit the conditions or adjustment required. Changes in the location of the cam B² may result from the bending or other misshaping of the hood B after the latch is installed, or may result from changing the position of the cam itself on the hood.

The adaptability of the latch to longitudinal movement of the hood is illustrated in Figure 2. The hook B³ is roughly concentric with the conicity of the flange B² and as the hood B is moved to the right or to the left the latch automatically adjusts itself to change in position such as are shown in Figure 2.

Figure 3 illustrates diagrammatically the adaptability of the latch to outward movement of the hood B, although obviously a hood conformation such as shown in Figure 3 would not be used in practice.

Obviously the amount of variation in position of the hood relative to the pin C as shown by the drawings herein is not likely to exist in practice. The aperture D³ is of course made of such length as to permit any usual vertical adjustment and the socket members C¹ and C² are so proportioned as to permit sufficient movement of the pin C to permit any degree of longitudinal or transverse movement of the hood B as is likely to take place in practice. The variations in position herein shown are far greater than are likely to occur in the practical operation of any automobile.

Thus I have invented a peculiarly effective and efficient type of automobile hood latch which is adaptable to a wide range of adjustments, to changes in location of the securing means on the hood, and to changes in the dimensions of the hood itself, when bent or twisted, without loss of efficiency. While always exerting both downward and inward pressure along and against the hood it permits vertical, longitudinal or transverse movement of the hood without binding and without losing its grip on the hood.

I claim:

1. In combination with a closure and a latch support, a latch for said closure, mounted upon said support, a hook element mounted on said closure, and a cam element mounted therebeneath on said closure, said latch including a member adapted to engage said hook, and a cam element in opposition

to said cam upon said closure and means for yieldingly moving said latch downwardly along said support.

2. In combination with a closure and a latch support, a latch for said closure mounted upon said support, a cam element mounted on said closure, and a cam element on said latch, in opposition to said cam upon said closure, opposed, interlocking members on hood and latch, adapted to hold said latch against movement laterally away from said closure, and means for yieldingly moving said latch downwardly along said support.

3. In combination with a closure and a latch support, a latch for said closure mounted upon said support, opposed cam members upon said latch and closure adapted in response to downward movement of the latch to direct both a downward and an inward pressure against said closure, a member mounted on said closure and adapted to engage said latch and to prevent outward movement of the latch away from the closure, while permitting generally vertical movement of said latch in relation to said closure, and means for yieldingly moving said latch downwardly along said support.

4. In combination with a closure and an abutment therefor, a latch support adjacent said abutment, mounted for universal movement, a latch member slidably mounted on said support, yielding means adapted normally to thrust it downwardly therealong, and a cam connection between said latch member and said closure adapted to thrust said closure downwardly and inwardly in response to downward movement of said latch member and means, for preventing lateral movement of said latch away from the hood during its operative engagement with the cam.

5. In a combination with a closure and an abutment therefor, a latch support adjacent said abutment, mounted for universal movement, a latch member slidably mounted on said support, yielding means adapted normally to thrust it downwardly therealong, a downwardly and outwardly inclined cam member upon said closure and a lug on said latch adapted to engage it and means for preventing lateral movement of said latch away from the hood during its operative engagement with the cam.

6. In a combination with a closure and an abutment therefor, a latch support adjacent said abutment, mounted for universal movement, a latch member slidably mounted on said support, yielding means adapted normally to thrust it downwardly therealong, a downwardly and outwardly inclined cam member upon closure and a lug on said latch adapted to engage it, a hook element mounted on said closure and above said cam and adapted to engage said latch.

7. In combination with a closure and an abutment therefor, a latch support mounted adjacent said abutment, a latch member slidably mounted upon said support, yielding means adapted normally to thrust it downwardly therealong, a downwardly and outwardly inclined, upwardly concave, conic cam mounted on said closure and a lug mounted on said latch member and adapted to engage said cam. 70
8. In combination with a closure and an abutment therefor, a latch support mounted adjacent said abutment, a latch member slidably mounted upon said support, yielding means adapted normally to thrust it downwardly therealong, a downwardly and outwardly inclined, upwardly concave, conic cam mounted on said closure, a lug mounted on said latch member and adapted to engage said cam, and a hook element above said cam positioned substantially on the axis of such cone and adapted to engage said latch. 75
9. In a combination with a closure and an abutment therefor, a latch support adjacent said abutment, mounted for universal movement, a latch member slidably mounted on said support, yielding means adapted normally to thrust it downwardly therealong, a downwardly and outwardly inclined cam member upon said closure and a lug on said latch adapted to engage it, said lug being perforated, a hook element mounted on said closure and above said cam and adapted to penetrate said aperture, and a stop member at the outer end of said hook adapted to prevent the escape of said lug from said hook. 80
10. In combination with a closure and an abutment therefor, a latch support adjacent said abutment, a ball and socket mounted therefor, a latch member slidably mounted on said support, yielding means adapted normally to thrust it downwardly therealong, and a cam connection between said latch member and said closure adapted to direct a thrust against said closure both downwardly and inwardly, in response to downward movement of said latch member, and means mounted on the hood, for limiting the movement of the latch away from the hood. 85
11. In combination with an automobile, a hood, a latch member mounted adjacent said hood, and a universal connection therefor, means on said latch for exerting pressure against said hood, and additional means for holding said latch member against swinging movement outwardly from said hood when it is in latching engagement. 90
12. In combination with an automobile, a hood, a latch member mounted adjacent said hood, and a universal connection therefor, means on said latch for exerting pressure against said hood, and additional means for holding said latch member against swing- 95
- ing movement outwardly from said hood when it is in latching engagement, while permitting swinging movement of said latch member in a plane parallel to the plane of said hood. 100
13. In combination with an automobile, a hood, a latch member mounted adjacent said hood, and a universal connection therefor, means on said latch for exerting pressure against said hood, and additional means for holding said latch member against swinging movement outwardly from said hood when it is in latching engagement, while permitting generally vertical movement of said latch member. 105
14. In combination with an automobile, a hood, a latch member mounted adjacent said hood, a universal connection therefor, means for holding said latch member against swinging movement outwardly from said hood when it is in latching engagement, and a cam connection between said latch and said hood adapted to direct pressure both downwardly and inwardly against said hood, in response to downward movement of said latch, independently of movement of said hood in any direction, after the latch is secured. 110
15. In combination with a closure and a latch for said closure, a rigid retaining member mounted on said closure and adapted to maintain a vertically slidable connection with said latch, when it is in a latched position, and to prevent lateral movement of the latch away from said closure. 115
16. In combination with a closure and a latch for said closure, and yielding means for holding said latch in a vertically oscillatory engagement with said closure, a stop member mounted on said closure, and adapted to engage said latch and limit relative movement of latch and closure when the latch is in operative position. 120
17. In combination with a closure and a latch for said closure, a rigid retaining member mounted on said closure and adapted to maintain a slidable connection with said latch, when it is in latch position, and to prevent lateral movement of the latch away from said closure. 125
18. In combination with a closure and a latch for said closure, and yielding means for holding said latch in engagement with said closure, a stop member mounted on said closure, and adapted to engage said latch and limit relative movement of latch and closure when the latch is in operative position. 130
19. In combination with a closure and a latch support, a latch for said closure, mounted upon said support, a hook element mounted on said closure, and a downwardly and outwardly inclined cam element mounted therebeneath on said closure, said latch including a member adapted to engage said

- hook, and a cam element in opposition to said cam upon said closure, and means for yieldingly moving said latch downwardly along said support.
- 5 20. In combination with a closure and a latch support, a latch for said closure mounted upon said support, a downwardly and outwardly inclined cam element mounted on said closure, and a cam element on said latch, 10 in opposition to said cam upon said closure, opposed, interlocking members on hood and latch, adapted to hold said latch against movement laterally away from said closure, and means for yieldingly moving said latch 15 downwardly along said support.
21. In combination with an automobile, a
- hood, a latch member mounted adjacent said hood, means for holding said latch member against swinging movement outwardly from said hood when it is in latching engagement, 20 comprising a lug on said latch and a member on said hood adapted to engage said lug, and a cam connection between said latch and said hood adapted to direct pressure both downwardly and inwardly against said hood, in 25 response to downward movement of said latch.

Signed at Chicago, county of Cook and State of Illinois, this 10th day of February, 1925.

CHARLES B. GILMORE.
